UNITED STATES PATENT OFFICE.

JAMES ADAIR, OF LEET TOWNSHIP, ALLEGHENY COUNTY, PENNSYLVANIA.

RACK FOR PENCILS, PENHOLDERS, &c.

SPECIFICATION forming part of Letters Patent No. 746,281, dated December 8, 1903.

Application filed September 3, 1903. Serial No. 171,793. (No model.)

To all whom it may concern:

Be it known that I, JAMES ADAIR, a citizen of the United States, residing in Leet township, in the county of Allegheny and State of Pennsylvania, have invented or discovered certain new and useful Improvements in Racks for Pencils, Penholders, &c., of which improvements the following is a specification.

The invention described herein relates to certain improvements in pen-racks of the class or type embodying as the gripping and holding element resilient or yielding members, such as a wire coil, a metal strip bent to serpentine form, &c. As heretofore constructed, the gripping or holding element consisting of laterally-moving members is so arranged on or secured to the base that all or the major portion thereof projects above the top or surface of the base and except by restricting its movement and efficiency cannot be supported and protected as against distortion arising from passing the hand along the coil or prying sidewise with a pen. Furthermore, when the gripping element has its members secured to the base the insertion of a pencil will cause adjacent coils to assume opposite inclinations, and the pressure of such oppositely-inclined coils against the smooth surface of the pencil will tend to force the latter out of the coil.

The object of the invention described herein is to provide a shield or guard for the gripping or holding element, so that the latter is unrestricted in its movements and inaccessible except by a pencil or penholder or other similar article.

It is a further object of the invention to provide for so securing the coil in the holder cage or shell as to avoid the necessity of special skill or devices for that purpose.

The invention is hereinafter more fully described and claimed.

In the accompanying drawings, forming a part of this specification, Figure 1 is a top plan view of my improved pen-rack. Figs. 2 and 3 are sectional views on planes indicated by the lines II II and III III, respectively, on Fig. 1. Figs. 4 and 5 are sectional and plan views of a portion of a rack, illustrating a modification of my improvement. Figs. 6 and 7 are sectional and end elevations of a modified form of rack. Figs. 8 and 9 are

plan and end elevations of a further modification of my improved rack. Figs. 10 and 11 are plan and end elevations of a modification of the construction shown in Figs. 8 and 9, and Figs. 12 and 13 are longitudinal and transverse sections illustrating a serpentine gripping element with a raceway suitably shaped therefor.

In the practice of my invention I provide a shell or case 1, the upper portion of which has its sides parallel or approximately parallel and a little larger than the diameter of the gripping or holding element 2, which is to be placed in the shell. The straight sides of the upper portion or raceway of the shell are connected by portions or contour of which corresponds to the transverse contour of the gripping element. The raceway or upper portion of the shell or case is divided into bars and spaces by cutting away or omitting portions thereof, thus leaving a series of arches or plates 3, forming a cage, which extends over the gripping element. The spaces between the several arches or plates should have a width at least equal to the diameter of the pencil or penholder or other article to be placed therein, while the arch or plate should be wide enough to extend beyond two adjacent members of the gripping element or to more than bridge the space between them. The end walls or abutments 4 of the case or shell have their edges turned over, forming sockets for the ends of the coil, as clearly shown in Figs. 1 and 2. The lower portion of the case or shell is preferably made somewhat wider than the upper portion, so that the completed rack will not readily turn over, and in this lower portion of the shell is placed a block 5, which fits therewith. This block may be made of heavy material or suitably weighted to prevent any tipping of the rack and bears against shoulders of the case or shell. The block may be made to extend into the vertical portion of the cage or raceway to form a bearing or seat for the gripping element; but to hide dust it is preferred to form a supporting-rib 7 on the block adapted to serve as a seat or bearing for the gripping element. By this construction—*i. e.*, by the employment of such a shell, case, or cage—the gripping element as it comes from the shaping mechanism can be cut off any desired lengths, placed within

the upper portion of the cage or shell, and the block 5 then fitted into the bottom portion, thereby securing the gripping element in position without the use of tools or skill or any 5 other fastening or securing devices, such as are now commonly used. The arches may be bent transversely, as shown in Figs. 12 and 13, thereby strengthening the arches and providing guiding-surfaces to direct the pencil, 10 &c., to the gripping element.

In lieu of a series of arches 3, formed integral, as stated, with the shell, the gripping element may be protected by means of arches or curved plates 8, formed on the upper ends 15 of the pins 9, which are driven down between adjacent members of the gripping element into the supporting base or rib 7. (Shown in Figs. 4 and 5.) The end walls of the cage or shell in this construction, as also that shown 20 in Figs. 1, 2, and 3, are formed with sockets for the reception and protection of the ends of the gripping element.

As shown in Figs. 10 and 11, the abutments or sockets for the reception of the ends of 25 the gripping element may be formed by arches provided along one edge with teeth or projections 12, which are bent inwardly to form bearings for the ends of the gripping element. When employing these annular abutments 30 or sockets and a coil, as the gripping element, a penholder or pencil can be inserted longitudinally into the coil.

As shown in Figs. 6 and 7, a pen-rack for one or more penholders or pencils can be 35 formed by recessing the inner faces of two blocks 10 of wood or metal to form sockets for the reception of the ends of the coil and then securing such blocks together in any desirable manner with their recessed portions 40 facing each other, as shown.

As shown in Figs. 8 and 9, the protecting arches or plates 3 may extend entirely or almost entirely around the gripping element and be secured to a base-plate 11, formed of 45 metal or other suitable material.

In lieu of the construction shown in Figs. 8 and 9 I may employ that shown in Figs. 10 and 11, wherein the arches are formed by fingers 13, extending from the side edges of the 50 base-plate 11 and bent around over the gripping element. It is preferred that the meeting ends of these fingers should be connected together. The end arches thus formed may be provided with inwardly-projecting teeth 55 to form bearings for the ends of the gripping element. These constructions are especially convenient when the rack is secured to a wall or desk.

The gripping element consists, as shown, 60 of a series of members held in yielding relation to each other and to the rigid arches, so that the pencil, &c., may be inserted between two adjacent members and when in position will be gripped by such members or be forced 65 against an arch, thus augmenting the frictional contact. A convenient embodiment or construction of the gripping element con-

sists of a coil of resilient wire, as shown in Figs. 1 to 11, or of a strip of resilient material, as metal, bent to serpentine form, as 70 shown in Figs. 12 and 13. It will be observed that the cage or raceway may be made angular in cross-section, conforming to the cross-sectional contour of the serpentine gripper.

The essential features or elements of my 75 improvement consist of a supporting-frame, which in one form may be a plain plate or strip, and protecting arches or plates above the gripping element and extending sufficiently around it to afford efficient protection 80 and at the same time to resist thrust against the pencil increasing frictional grip, while dispensing with all holding-down devices now in use. In the construction shown in Figs. 1, 2, 3, 6, 7, 10, and 11 the end arches or plates 85 are formed integral with the support-frame.

It is characteristic of my improvement that the gripping element is arranged within a raceway or cage, which will protect it from distortion or injury and so supports or contains 90 the gripping element that no fastening devices are required, and perfect freedom of movement of all members of the gripping element is permitted, while the hold on the pencil, &c., is augmented in some cases by frictional contact with the rigid uprights of the arches. As the arches are spaced a distance apart a little greater than the diameter of the pencil or other article to be held, a prying movement of the pencil such as would distort 100 the gripping element is prevented, and distortion from passing the hand over the gripping element is impossible, as the finger cannot pass between the arches.

I claim herein as my invention—

1. A rack for pencils, penholders, &c., having in combination a base or support having end walls or abutments provided with sockets, and a gripping element having its ends arranged in said sockets and held in position 110 thereby, substantially as set forth.

2. A rack for pencils, penholders, &c., having in combination a base or support, a gripping element, and one or more protecting arches or plates arranged above the gripping 115 element, substantially as set forth.

3. A rack for pencils, penholders, &c., having in combination a shell or raceway having portions cut away to form protecting arches or plates and a gripping element arranged 120 within the shell or case, substantially as set forth.

4. A rack for pencils, penholders, &c., having in combination a shell or raceway provided with end walls or abutments and having protecting arches or plates intermediate of its ends, a block provided with a rib for supporting the gripping element and a gripping element arranged with the shell or raceway, substantially as set forth.

5. A rack for pencils, penholders, &c., having in combination a shell or raceway provided with end walls or abutments having sockets and with intermediate protecting

arches or plates, and a gripping-coil formed of resilient material arranged within the raceway, substantially as set forth.

6. A rack for pencils, penholders, &c., having in combination a shell or raceway having annular end walls or abutments provided with sockets, and a gripping-coil formed of resilient material arranged within the raceway, the ends of the coil projecting into the sockets and held in position in the raceway by the sockets, substantially as set forth.

7. A rack for pencils, penholders, &c., having in combination a shell or raceway having annular end walls or abutments provided with sockets, and having intermediate arches or plates, and a gripping-coil formed of resili-

ent material arranged within the raceway, substantially as set forth.

8. A rack for pencils, penholders, &c., having in combination a shell or case provided with end walls and having protecting arches or plates intermediate of its ends, a gripping element arranged in the case or shell and a supporting-block for the gripping element secured in the case or shell, substantially as set forth.

In testimony whereof I have hereunto set my hand.

JAMES ADAIR.
